UNITED STATES PATENT OFFICE.

MANUEL A. T. GILLBEE, OF PHILADELPHIA, PENNSYLVANIA.

DESIGN FOR A PICTURE FRAME OR MOUNT.

SPECIFICATION forming part of Design No. 28,806, dated June 7, 1898.

Application filed April 6, 1898. Serial No. 676,704. Term of patent 7 years.

To all whom it may concern:

Be it known that I, MANUEL A. T. GILLBEE, a citizen of the United States, residing in Philadelphia, Pennsylvania, have invented a certain new and original Design for a Picture-Frame, of which the following is a specification.

My design consists in a novel ornamentation for a picture frame or mount and is fully shown in the accompanying drawing, which represents a face view of a picture frame or mount having my design thereon.

In each corner of the card forming the frame or mount is a scroll-like ornamentation, the ornamentation in the upper corners differing slightly from that of the lower corners.

The essential feature of the design is the scroll-like ornamentation in the corners of the frame or mount.

I claim—

The design for a picture frame or mount, consisting of a card having ornamentation thereon, substantially as herein described and shown in the accompanying drawing.

In testimony whereof I have signed my name to this specification in the presence of two subscribing witnesses.

MANUEL A. T. GILLBEE.
